[57] ABSTRACT

A trampoline includes an inflated elastomeric toroid, such as a tire inner tube, provided with taut top and bottom webs interconnected by straps extending between the webs about the tube outer surface. A stabilizer against tipping is separably associated with the trampoline and extends around the tube outer underface. Examples of stabilizers are circumferentially spaced hollow stackable wedge shaped foot pieces separably connected at their inner ends to the bottom web and engaging the tube underface, diametric cross-bars sandwiched between the tube and bottom web and projecting beyond the tube, outwardly directed loops secured to the bottom webs and holding stabilizing members below the tube outer face, and a narrow inflated torus underlying the tube inner under face.

STABILIZED TRAMPOLINE

BACKGROUND OF THE INVENTION

The present invention relates generally to improvements in exercising and amusement devices and it relates more particularly to an improved trampoline of the pneumatic type.

Trampolines are highly popular as an exercising and amusement device but the conventional trampolines are expensive and bulky devices requiring firm foundations and careful erection and considerably available space. A trampoline which overcomes the aforesaid drawbacks of the conventional trampoline is of the pneumatic type which includes an inflated tire inner tube having a web tautly secured across the top thereof. This type of trampoline is generally satisfactory and possesses numerous advantages being relatively small, suitable for both indoor and outdoor use, and may be collapsed to a highly compact state for storage, shipping and handling purposes. However, the pneumatic type of trampoline is an unstable structure in that it has a tendency to tilt toward overturning when force is applied to its peripheral border. Thus, the pneumatic type of trampoline unless it is very carefully employed may present the danger of physical injury to the user.

SUMMARY OF THE INVENTION

It is a principal object of the present invention to provide an improved exercising and amusement device.

Another object of the present invention is to provide an improved trampoline.

Still another object of the present invention is to provide an improved pneumatic type of trampoline.

A further object of the present invention is to provide an improved trampoline of the type including an inflated tire inner tube body member having an overlying flexible web attached thereto and possessing high resistance to overturning.

Still a further object of the present invention is to provide a highly stable pneumatic trampoline of the above nature characterized by its ruggedness, simplicity, convenience, use, its ready collapsibility to a compact state for storage, packaging and shipping purposes and its great versatility and adaptability.

The above and other objects of the present invention will become apparent from a reading of the following description taken in conjunction with the accompanying drawings which illustrate preferred embodiments thereof.

In a sense the present invention contemplates the provision of a pneumatic trampoline comprising an inflated elastomeric tubular member of substantially toroidal shape, a flexible first web overlying the top of said inflated member, means securing said web to said inflated member, and separate stabilizing means located around and underlying the bottom face of said inflated member externally of the bottom periphery thereof.

In its preferred form the body member of the improved trampoline is an inflated tire inner tube. Webs are tautly drawn across the top and bottom of the inner tube by straps interconnecting the borders of the webs and extending about the tube outer surface. The stabilizing means includes a plurality of circumferentially spaced open bottom wedge shaped foot pieces having curved inner faces engaging the outer underface of the tube. Means are provided for securing the inner ends

of the foot pieces to the bottom web or between the bottom web and tube. The preferably hollow footpiece walls may converge upwardly to facilitate the nested stacking thereof. Such foot pieces may be shaped wire members having outer cross members terminating in inwardly directed legs projecting between the tube and bottom web. In an alternative stabilizer structure a plurality of angularly related slats extend diametrically between the bottom web and tube and project beyond the tube outer periphery. The slats may be conveniently constructed to be collapsible. In another form flexible loops secured to the border of the bottom web and beyond the tube outer periphery may releasably engage footpieces which underlie outer underface of the tube. A narrow inflated torus may be employed as a stabilizer, underlying and engaging the outer underface of the tube.

BRIEF DESCRIPTION OF THE DRAWINGS

FIG. 1 is a front perspective view of a trampoline embodying the present invention;

FIG. 2 is an enlarged fragmentary sectional view taken along line 2-2 in FIG. 1;

FIG. 3 is a fragmentary bottom view thereof;

FIG. 4 is a sectional view taken along line 4-4 in FIG. 3;

FIG. 5 is a medial longitudinal sectional view of a plurality of footpieces of the above embodiment shown in stacked condition;

FIG. 6 is a side elevational view of another form of foot piece and connector;

FIG. 7 is an enlarged sectional view taken along line 7-7 in FIG. 6;

FIG. 8 is a fragmentary vertical sectional view of another embodiment of the present invention taken along line 8-8 in FIG. 9;

FIG. 9 is a bottom plan view thereof;

FIG. 10 is a bottom plan view of another embodiment of the present invention;

FIG. 11 is a perspective view of one of the stabilizing elements in the embodiment of FIG. 10, shown in a separated detached state;

FIG. 12 is a fragmentary longitudinal sectional view thereof shown in a connected state;

FIG. 13 is a view similar to FIG. 12 of another form of stabilizing member;

FIG. 14 is a fragmentary bottom plan view of another embodiment of the present invention;

FIG. 15 is a fragmentary vertical sectional view of still another embodiment of the present invention;

FIG. 16 is a perspective view of a separable stabilizing member thereof;

FIG. 17 is a fragmentary vertical sectional view of further embodiment of the present invention;

FIG. 18 is a perspective view of a separable stabilizing member thereof;

FIG. 19 is a fragmentary vertical sectional view of another embodiment of the present invention;

FIG. 20 is a perspective view of a separable stabilizing member thereof; and

FIG. 21 is a fragmentary vertical sectional view of another embodiment of the present invention;

DESCRIPTION OF THE PREFERRED EMBODIMENTS

Referring now to the drawings and more particularly FIGS. 1 to 5 thereof which illustrate a preferred em-

bodiment of the present invention, the reference numeral 10 generally designates the improved pneumatic trampoline which includes a body member or main section 11 and a stabilizer section 12. The main section 11 is of broadly conventional construction, except as will be hereinafter described, and is substantially of the same structure in all the embodiments of the present invention, but modified to cooperate with the particular associated stabilizer section. It should be noted that the subject invention may be advantageously employed with pneumatic main sections specifically different from those described and illustrated.

The main section 11 includes a horizontal inflated toroid 13 having an elastomeric wall and is advantageously a vehicle tire rubber inner tube of suitable size provided with a conventional tubular stem housed inflation valve such as of the Shroeder type. A strong flexible, preferably woven fabric, substantially circular top web 14, for example formed of canvas, heavy muslin or the like, overlies the central opening of the inflated toroid 13 with its border extending to or shortly outwardly of the top periphery 16 of inflated toroid 13, it being noted that the peripheral border of top web 14 may be scalloped and provided with a plurality of radially projecting apices 17. A bottom web 18 generally similar in shape and construction to top web 14 underlies the inflated toroid 13 and extends to at least the bottom periphery 19 thereof.

The top and bottom web 14 and 18 are separably secured to the inflated toroid 13 and maintained in a taut condition by a plurality of flexible straps or woven bands 20, each band 20 having one its opposite ends secured, such as by sewing to diametrically opposed apex points on the bottom web 18 and extending about the outer surface of inflated toroid 13 and diametrically across the top thereof between corresponding diametrically opposed top web apices 17 to which the strap 20 is secured by sewing or the like. It should be noted that straps 20 may be secured to top web 14 at other points and may be secured to each other at their area of intersection which registers with a circular opening 21 formed in top web 14. The toroid 13 is advantageously sufficiently inflated to draw webs 14 and 18 and straps 20 very taut, the wall sections 22 of inflated toroid 13 delineated by the edges of webs 14 and 18 and straps 20 being outwardly distended into bulbous sections.

The stabilizing section 12 comprises a plurality of circumferentially spaced wedge shaped chocks on foot pieces 23 which are of hollow approximately prism shape, open at their bottoms and formed of any suitable material such as synthetic organic thermoplastic resins, for example the polyolefins, polyvinyl chloride or the like. Each chock 23 includes an upwardly inwardly inclined outer wall 24, an upwardly outwardly inclined, upwardly concave arcuate inner wall 26 mating the outer bottom face of inflated toroid 13, walls 24 and 26 converging to a rounded apex, and upwardly converging triangular side wall 27. Each of the chock walls 26 includes an inwardly projecting flat tongue 29 coplanar with the bottom of chock 23 and terminating in a pair of integrally formed laterally spaced outwardly directed hook defining legs 30 disposed below the tongue 29.

Disposed on the underface of bottom web 18 shortly inwardly of the toroid bottom periphery 19 and in alignment with the ends of bands 20 are short bands 32 parallel to the border of bottom web 18 and secured at

their ends to web 18 to delineate respective narrow passageways slightly greater than the widths of tongues 29.

In the erected operative position of the trampoline 10 a chock 23 registers with the ends of each strap 20, the chock surface 26 matingly engaging the outer under face of inflated toroid 13 through respective straps 20 and resting in the valleys between successive protuberances 22. The chock tongues 29 project through the passageways above bands 32, the hooks 30 engaging the inner borders of bands 32 thereby preventing the separation and outward movement of the chocks. The chocks 23 shift the overturning axes of the trampoline 10 outwardly from the toroid bottom periphery 19 to the bottom edges of chock walls 24 thereby radically improving the stability of the trampoline 10.

In disassembling and collapsing the trampoline 10 the chocks are separated from the trampoline by pushing the individual chocks inwardly to effect disengagement of bands 32, by hooks 30, spreading the space between band 32 and bottom web 18 and withdrawing the tongues 29 and hooks 30 therethrough. The chocks 23 may be stacked in a compact nested condition, as shown in FIG. 5, by reason of the open bottom and converging walls thereof. The webs and deflated inner tube may be likewise collapsed to a compact condition. The stabilized trampoline 10 may be erected by a procedure opposite to that effecting its collapse as described above.

The trampoline illustrated in FIGS. 6 and 7 differs from the trampoline 10 described above only in the arrangement for separably connecting the chocks to the body member, the trampoline being otherwise the same. Specifically the modified trampoline includes a bottom web 33 corresponding to bottom web 18 and associated inflated toroid 13a, top web and interconnecting straps. Located on the underface of web 33 proximate its borders are a plurality of circumferentially spaced bands 34 corresponding to bands 32, bands 34 being sewn at their ends to web 33. Medially formed in each band 34 is an opening which is engaged by a grommet 36 which may be the socket member of a snap type separable fastener.

The associated chocks 37 are similar in shape and construction to chocks 23, and include inwardly directed tongue sections 38. Each tail section is provided proximate its free end with an integrally formed depending plug or peg 39 which separably engages the corresponding grommet 36, the inner end of tongue 38 slideably registering with the passageway between bottom web 33 and respective band 34 and the curved inner face of chock 37 engaging the bottom outer face of the trampoline inflated toroid 13a. The assembly, erection, disassembly and use of the trampoline last described is similar to that of trampoline 10.

In FIGS. 8 and 9 of the drawing there is illustrated another form of trampoline 40 embodying the present invention differing from trampoline 10 in the shape of the chocks and their coupling to the trampoline body. The trampoline 40 includes an inflated toroid 41, a bottom web 42, and a top web and interconnecting straps (not shown) in the manner of trampoline 10, the coupling bands 32 of trampoline 10 being omitted. It should be noted that there are radial passageways between the confronting faces of toroid 41 and bottom web 42 having outwardly facing openings 43 separated by successive web connecting straps.

The stabilizing section of trampoline 40 comprises a plurality of circumferentially spaced separable stabilizing members 44. Each stabilizing member 44 includes a flat base plate 46 provided with an inwardly projecting tongue section 47 integrally formed with the outer section of each base plate 46 is an open bottom chock defining section including upwardly converging curved concave inner wall 48, outer wall 49 and side walls 50 corresponding in shape to walls 26, 24 and 27 of chocks 23, thereby permitting the stacking of detached stabilizing members 44.

In the assembled condition of the trampoline 40, the stabilizing members 44 are circumferentially positioned about the inflated toroid 41, the tongue sections 47 thereof projecting between and embraced by the confronting faces of inflated toroid 41 and bottom web 42 between successive web connecting straps, and the chock walls 48 directly engaging the outer underface of the inflated toroid 41. The erection, assembly and use of trampoline 40 is clear from the above.

Referring now to FIGS. 10 to 12 of the drawings which illustrate another embodiment of the present invention differing from those earlier described in the construction and arrangement of the stabilizing members. The body member of the trampoline 51, includes an inflated toroid 52, a bottom web 53 underlying toroid 52, a top web overlying toroid 52 and connected to bottom web 53 by a plurality of straps corresponding to straps 20, access between bottom web 53 and toroid 52 being provided between successive web connecting straps.

The stabilizing section includes a plurality of angularly related bars or slats 54 which extend diametrically across the bottom of the inflated toroid 52 and overlie bottom web 53. The slats 54 intersect preferably at the bottom center of toroid 52 and project beyond the toroid outer periphery. The opposite sections of slats 54 inwardly of the ends thereof are sandwiched between the confronting faces of bottom web 53 and toroid 52 and project through the passageways delineated thereby. In order to facilitate the compact storage of the stabilizing slats 54, each slat 54 may include at least two separable end sections 56 and 57 provided with mating separable coupling sections. For example slat section 57 is provided with a longitudinal end tongue 58 of reduced transverse cross section and slat section 56 is provided with a mating end socket which is engaged by a respective end tongue 58.

As shown by way of example in FIG. 13 other forms of stabilizing slats of a collapsible nature may be provided. For example, each stabilizing slat 58, which functions in the manner of slats 54 comprises a plurality of tubular longitudinal end to end sections 59 which are detachably rigidly interconnected by plug elements 60 separably telescopically engaging confronting ends of adjacent sections 59.

In FIG. 14 of the drawings there is illustrated another form of stabilizing system which may be advantageously employed with the improved pneumatic trampoline 63. Trampoline 63 has a body member similar to that described above including an inflated toroid 64 and a bottom web 65, as well as a top web and interconnecting straps.

The trampoline stabilizing system includes a plurality of circumferentially spaced side by side foot pieces 66 formed of heavy wire, bar or the like. Each foot piece includes a cross member which may be linear on arcu-

ately concentric with toroid 64 and which terminates at opposite ends in inwardly radially converging side legs 68. Side legs 68 of adjacent foot pieces 66 are parallel and juxtaposed and separably medially radially project through the passageways delineated, and being embraced by the confronting faces of bottom web 65 and toroid 64. In the assembled condition of the foot pieces 66 and the trampoline body member, the foot piece cross members 67 are located radially outwardly of the outer periphery of inflated toroid 64 and are in substantially end to end relationship. In the assembly and disassembly of the stabilized trampoline last described the foot piece legs 68 are respectively slideably inserted or retracted from between toroid 64 and bottom web 65.

Referring now to FIGS. 15 to 20 of the drawings which illustrate embodiments of the present invention which differ from the trampolines first described primarily in the chock attaching arrangements these embodiments differing from each other in the specific shapes of the chocks. The body of the trampoline in each case includes an inflated toroid 70, a top web 71 overlying the top of toroid 70, a bottom web 72 underlying the toroid 70, webs 71 and 72 being interconnected by cross straps as in the earlier described trampolines.

A plurality of circumferentially spaced flexible loop members 73 are secured to the border of bottom web 72 and project radially therefrom. Each loop member 73 is formed of a flexible, preferably woven, band 74 having overlapping ends stitched or otherwise connected to bottom web 72.

In the embodiment shown in FIGS. 15 and 16 each of the loops 73 releasably engages a hollow open bottom chock 76. Each chock 76 includes an upwardly concave arcuate inner wall 77 and an upwardly inwardly inclined outer wall 78, walls 77 and 78 converging upwardly to a rounded apex 79, and upwardly slightly converging side walls 80. A longitudinal channel 81 of about the width of band 74 is formed in inner and outer walls 77 and 78 and is bordered by parallel ridges 82. The bottom borders of walls 77 and 78 are inwardly curved as at 83. In the assembled and erected condition of the trampoline last described a chock 76 registers with each loop 73 which engages the respective groove 81, and the loops 73 are of such size and the chocks 76 of such size and configuration that the outer underface of inflated toroid 70 rests on chocks 76 and is engaged by chock walls 77 thereby greatly increasing the stability of the trampoline. In the disassembled condition of the trampoline the chocks 76 may be stacked in nested condition.

The embodiment of the present invention illustrated in FIGS. 17 and 18 differs from that last described only in that rectangular wooden blocks 83 are substituted for the chocks 76. The blocks 83, which may be short pieces of a conventional 2 x 4 are separably medially engaged by respective loops 73 with the blocks 83 resting on their narrow sides. The loops 73 and blocks 83 are so dimensioned and related that in the trampoline erected condition the upper inner edges of blocks 83 engage or are closely proximate the upper portion of the bottom outer face of inflated toroid 70 when loops 73 are fully extended.

In the embodiment of the invention illustrated in FIGS. 19 and 20, in place of the chocks 76 or blocks 83 there are employed as foot pieces cylindrical mem-

bers which are the conventional sheet metal cans in which beverages are marketed and dispensed or any other similar cylindrical can. The cans 84 are medially separably engaged by respective loops 73 which are of such size and disposition as to retain the cans 84 against the outer bottom face of the inflated toroid 70 when the letter is in use thereby outwardly extending the trampoline overturning axis and increasing its stability.

The improved trampoline 86 shown in FIG. 21 of the drawing, like in the earlier embodiments, comprises an inflated toroid 87 provided with top and bottom webs interconnected by straps corresponding to webs 14 and 18 and straps of the trampoline 10. In order to maintain the trampoline 86 in a stable condition and inhibit the overturning thereof there is provided a torus shaped stabilizing member 88 which peripherally releasably engages the outer bottom face of inflated toroid 87 along a circumference between the outer and bottom peripheries of toroid 87 and in this condition the bottom peripheries of toroids 87 and 88 are advantageously coplanar. The stabilizing member 88 may be a hollow ring of a synthetic organic plastic or the like or may advantageously be an inflated elastomeric tube, such as, for example, an inflatable bicycle tire inner tube of suitable size.

While there have been described and illustrated preferred embodiments of the present invention, it is apparent that numerous alterations, omissions and additions may be made without departing from the spirit thereof.

What is claimed is:

1. In a pneumatic trampoline comprising an inflated elastomeric tubular member of substantially toroidal shape and a flexible first web overlying the top of said inflated member and means extending from said first web about said inflated tubular member securing said web to said inflated member, separable stabilizing means including a plurality of circumferentially spaced outwardly projecting foot pieces with their underfaces at substantially the level of the trampoline underface, each of said foot pieces including an inwardly downwardly inclined upper inner face engaging the outer underface of said trampoline, and means separably inter-

connecting said stabilizing means and said trampoline including means for separably securing the inner ends of said foot pieces to said web securing means.

2. The trampoline of claim 1, said web securing means including a second flexible web underlying said inflated member and flexible bands secured to said first and second webs and extending between said webs about the outer periphery of said inflated member.

3. The trampoline of claim 2 wherein said foot piece securing means comprises circumferentially spaced securing members disposed on the underface of said second web proximate the periphery thereof and defining radial passages therewith, the inner ends of said foot pieces traversing said passages, and hooks formed at the inner ends of said foot pieces releasably engaging the inner edges of securing members.

4. The trampoline of claim 2 wherein each of said foot pieces is hollow and open bottomed and includes upwardly converging walls to permit the nested stacking of said foot pieces.

5. The trampoline of claim 2 wherein said means for separably securing the inner ends of said foot pieces to said web securing means separably secures said foot piece inner ends to said second web.

6. The trampoline of claim 2 wherein said foot piece securing means comprises a plurality of circumferentially spaced first separable fastener elements positioned along the peripheral border of said second web and second fastener elements located proximate the inner ends of said foot pieces and releasably engaging said first fastener elements.

7. The trampoline of claim 6, wherein said fastener elements comprising mating plugs and sockets.

8. The trampoline of claim 2 wherein said separable securing means comprises an elongated tongue projecting inwardly from the base of each said foot pieces between said second web and said inflated member.

9. The trampoline of claim 1 wherein each of said foot piece inclined upper inner faces is of concave curvature and mates the underface of said inflated member.
